UNITED STATES PATENT OFFICE.

KYSTER B. COLEMAN, OF SCOTTSBURG, VIRGINIA, ASSIGNOR OF ONE-HALF TO JAMES E. GREEN, JR., OF CLOVER, VIRGINIA.

CROSSING-SIGNAL FOR RAILROADS.

1,241,608.

Specification of Letters Patent.

Patented Oct. 2, 1917.

Application filed September 22, 1915. Serial No. 52,084.

To all whom it may concern:

Be it known that I, KYSTER B. COLEMAN, a citizen of the United States, residing at Scottsburg, in the county of Halifax and State of Virginia, have invented certain new and useful Improvements in Crossing-Signals for Railroads; and I do hereby declare the following to be a full, clear, and exact description of the invention, such as will enable others skilled in the art to which it appertains to make and use the same.

This invention relates to new and useful improvements in track instruments for operating crossing signals for railroads and has for one of its objects the provision of a device of this character, which shall be simple, durable and efficient and which may be manufactured and sold at a comparatively small cost.

Another object of this invention is to provide a lever pivoted to the rail of a railroad track and is adapted to be engaged by a train for closing an electric circuit to a signal.

A further object of this invention is to provide a contact arm adapted to be moved by said lever to close an electric circuit, and which will remain in a circuit closing position under the influence of electro-magnets.

With these and other objects in view, the invention consists in the novel combination and arrangement of parts which will be fully set forth in the following specification and accompanying drawings, in which:

Figure 1 is a plan view of a railroad track showing the crossing signal applied thereto, said signal and operating mechanism thereof being in diagram.

Fig. 2 is an enlarged view showing the controlling switch.

Fig. 3 is a vertical sectional view on line 3-3 of Fig. 2, on an enlarged scale, and

Fig. 4 is a detail perspective view of the cut-out switch.

Referring now to the drawings by characters of reference, the numeral 1 designates a railroad rail of the ordinary construction, having secured to the base thereof in any suitable manner a bearing block

2. This bearing block has pivoted thereto as at 3, the lever 4, the upper end of which is provided with the roller 5 and the lower end of said lever is provided with an arm 6. This lever 4 is designed to control the

operation of the circuit closer which will

be more fully hereinafter described, when the wheel of the train passing over the device engages the roller 5. A suitable retractile coil spring 7 is connected near the free end of the arm 6 and the opposite end of said spring is connected to the base of the rail, so that the device will be automatically returned to its original position after having been operated when the current is discontinued through the signal, by the releasing switch which will be more fully hereinafter described.

Supported on a suitable insulating block 8 is a strip of metal 9, which is preferably a resilient or spring metal and this strip of metal is provided with a horizontal arm 10, the forward end of which is provided with the contact plate 11. The arm 10 is preferably of a relatively soft iron or similar material which may be easily attracted by a magnet and supported immediately beneath the arm are the electro-magnets 12, the cores 13 of which extend into close proximity to the arm as clearly shown in Fig. 2. A suitable stationary contact 14 is supported on an insulating block 15 and is positioned so that its upper end will be engaged by the contact plate 11 hereinbefore referred to. Leading from one of the magnets 12 is a wire 16, and leading from the contact post 14 is a wire 17 and these wires lead to the signal and battery associated therewith.

The wire 16 above referred to is connected to a suitable wire 18 which cooperates with the wire 19 in furnishing power to the light 20 and this wire 19 is connected by means of the wire 21 to the wire 22, which cooperates with the parallel wire 23 in furnishing power to the light 24. These lights 20 and 24 are positioned at opposite sides of a roadway so that when a train approaches, the same will be illuminated, thereby signaling any person traveling along the roadway of the danger. The wire 23 is connected by means of a suitable wire 25 to a circuit breaker which will be more fully hereinafter described.

The circuit breaker above referred to comprises a lever 26, which is pivoted as at 27 to a suitable plate 28 secured to the under side of the rail and this lever 26 is provided with the forward and downward extension 29, having the contact element 30 formed at its extreme forward end. This contact ele-

ment 30 is arranged to engage the contact arm 31 mounted on the standard 32 and the pivot point 27 of the lever 26 is connected to the wire 25, hereinbefore referred to. Ex-
5 tending outwardly from the base of the rail is a suitable plate 33 for the support of the compression coil spring 34, which bears against the under side of the lever 26 and forces the contact element 30 into engagement with the contact arm 31 so that the circuit under normal circumstances is completed through this device. A wire 35 leading from the standard 32 is connected to a suitable power source 36, the opposite terminal of which is connected to the wire 17 hereinbefore referred to.

It will be apparent from the foregoing that in use as the train passes over the circuit closing mechanism it will rock the arm 20 or lever 4, thus moving the arm 6 downwardly against the tension of the spring 7 so as to force the arm 10 downwardly and cause the contact to be made between the plate 11 and the standard 14. The passage 25 of the current from the battery 36 to the wire 17 to the standard 14 and thence through the contact 11 and arm 10 to the strip 9 and back through the wires leading through the magnet to the wire 16 will hold 30 the arm 10 in such a position as to keep the circuit completed even though the pressure on the wheel 5 may be released. The circuit is maintained through the magnet and thus through the lights 20 and 24 until the 35 flange of the car wheel passing over the rail engages the lever 26 of the circuit breaker thereby breaking the circuit between the contact point 30 and the arm 31. The lever 26 is of such a length as to hold the circuit 40 discontinued for a sufficient length of time to permit the resilience of the arm 10 to move said arm upwardly and thereby break the circuit between the contact point 11 and the standard 14. After the train has passed

over the lever 26, it will be seen that the 45 same will return to its normal upward position through the action of the spring 34 and the device will again be set ready for a second operation. In order to use this device in connection with trains traveling in opposite directions, it will be seen that the two 50 devices are necessary and may be connected as shown in Fig. 1 so as to light both sets of lights from either of the circuits. In this way, it will be seen that the necessity of providing a separate set of lights is unnecessary.

While in the foregoing there has been shown and described the preferred embodiment of this invention, it is to be understood 60 that such changes may be made in the combination and arrangement of parts as will fall within the spirit and scope of the appended claim.

What is claimed is:

65 A track instrument for railroad signals comprising a lever pivoted below a rail and projecting slightly above the rail, said lever being adapted to be engaged by a train when passing over the rail, an arm on the underside of the lever, and a spring normally holding the arm in a substantially horizontal position, of an L-shaped contact arm, adapted to be engaged by the end of the arm on the lever, a contact for engagement by the 70 contact arm, an electric circuit closed by said contact arm and magnets in series in said circuit and positioned beneath said contact arm whereby when the arm is initially moved to close the circuit the magnet will be 75 energized to hold said arm in circuit closing position.

80 In testimony whereof I affix my signature in presence of two witnesses.

KYSTER B. COLEMAN.
